IRA C. KELLEY, OF MONTICELLO, INDIANA, ASSIGNOR TO HIM SELF AND W. A. HUNT.

Letters Patent No. 91,545, dated June 22, 1869.

IMPROVEMENT IN ROSETTE-HOLDERS.

The Schedule referred to in these Letters Patent and making part of the same.

To all whom it may concern:

Be it known that I, IRA C. KELLEY, of Monticello, county of White, in the State of Indiana, have invented a new and improved Rosette-Holder; and I do hereby declare that the following is a full and exact description thereof, reference being had to the accompanying drawings, making a part of this specification, in which like parts are represented by like letters in the several figures.

The nature of my invention consists in forming a rosette-holder of three pieces, to be hereafter described, by which I am enabled to adjust the same easily, and secure and change the covering of the outside portion as often as desired; and it can be applied to various portions of the dress, such as the shirt, neck, and collar-bands, bosom, cuffs, or to attach rosettes to slippers, button-holes, &c.

In the drawings—

Figure 2 shows a section of my improved rosette-holder, consisting of the front or button-portion A, having a projection extending from its rear or under side, on which is cut a screw-thread, and upon which screws a cap, d, and into which also screws a button, b, having a screw-stem.

In Figure 4, a covering is shown secured to this stud.

To release it, the screw-cap d is run back far enough to withdraw the covering c from between the two. In

this condition, the outer edges of a new covering can be introduced, and the cap screwed up, or the cap can be entirely removed before adjusting the cover, which plan would, perhaps, be easier.

During the placing and removal of a covering, the parts A and d are detached from b, and to put the covered stud in place, the part b is inserted through a hole from the inside, when the part A, with its covering and holding-cap d, is screwed down upon it.

The covering c can be made in the shape of a bag with an open mouth, partially "drawn," by having a small rubber string in the same, but the cap renders such unnecessary. It may be useful, to save time.

Such a "drawn" covering would be necessary if applied to a button or stud composed of two parts, as shown in Figures 1 and 3.

Having thus described my invention,

What I claim as new, and desire to secure by Letters Patent of the United States, is—

An improved rosette-holder, consisting of the base A, over which the fabric is stretched, and the clamp d, which secures it thereon, and the screw-stud b, by which the device is attached, the whole arranged substantially as described.

IRA C. KELLEY. [L. S.]
